FLUID PUMP

BACKGROUND OF THE INVENTION

A fluid pump of the present invention belongs to the type of rotary pump which may be classified into (a) three-lobe pump (b) two-screw pump (c) external gear pump (d) sliding vane pump, but a special type of having upper and lower trains of plural rotors having two blades and recesses with their phase angles shifted each other, so that it transfers continuously and uniformly a greater amount of fluid with higher pressure and sucking head, without no priming fluid and cavitation, and under least vibration and noises.

SUMMARY OF THE INVENTION

The present invention provides a fluid pump comprising trains of upper and lower couples of rotors; the rotor having two blades and recesses at right angles; the blade fitting into the recess; each rotor phase angle shifting; and the rotors counterrotating to transfer a greater amount of fluid with higher pressure and sucking head under no cavitation.

BRIEF DESCRIPTION OF THE DRAWING

FIG. 1 is a cross section perpendicular to an axe of one preferred embodiment of the present invention.

FIG. 2 is an axial cross section of FIG. 1.

FIG. 3 is a squint view of a train of rotors.

DESCRIPTION OF THE PREFERRED EMBODIMENT

The fluid pump of the present invention will be described in more detail in connection with the preferred embodiment.

FIG. 1 shows a fluid pump having an 8-shape chamber 1 comprising three unit-casings 1a, 1b, 1c connected tightly by bolts 2, 2.

Cover plates 3, 3a cover the right and left opening sides of the chamber 1 by the bolts 2, 2 tightened.

Fluid storing rooms 4, 5 are mounted on bloc before and behind the chamber 1.

Connecting holes 6, 7 formed in the center of the chamber 1 make the insides of the fluid storing rooms 4, 5 to communicate with the inside of the chamber 1.

An inlet 8 and an outlet 9 are projected from the outsides of the fluid storing rooms 4, 5.

A main driving shaft 10 and a subject driven shaft 11 are horizontally bridged over in the chamber 1.

Each train of three couples of rotors 12, 12a, 12b and 13, 13a, 13b is mounted on the shafts 10, 11.

Partition walls 14, 14a, 14b projected inside the unit-casings 1a, 1b, 1c contact slidingly with each peripheral surface of the joint parts of the rotors 12, 12a, 12b and 13, 13a, 13b.

Two mutually opposed projecting blades 15, 15a and two opposed recesses 16, 16a are mounted on the peripheral surfaces of the rotors 12, 12a, 12b and 13, 13a, 13b at right angles.

The blades 15, 15a contact slidingly with the inside circular wall of the chamber 1. The recesses 16, 16a are concaved to fit the blades 15, 15a.

The rotors 12, 12a, 12b and 13, 13a, 13b are combined to fix with their phase angles shifting at 60°.

Gears 17, 18 are mounted on the shafts 10, 11 to mesh each other.

A containing room 19 of the choking plate 3a contains the gears 17, 18.

Accordingly when driving the main shaft 10 in connection with the prime mover, the subject shaft 11 will cooperate to drive forcibly the rotors 12, 12a, 12b and 13, 13a, 13b to revolve so that the blades 15, 15a of each upper or lower rotor

will fit into the recesses 16, 16a of each lower or upper rotor where the fluid sucked into the chamber 1 through the fluid storing room 4 from the entrance 8 will be forced onward along the circular inside wall and be pressed forward from the exit 9 through the fluid storing room 5.

The experimental results are shown in the following tables in case of testing ability of hydraulic power of the present fluid pump.

10

TABLE 1.—4 POLE, 3 PHASE, 2 HORSEPOWER MOTOR

Experiment No.	1	2	3	4	5
Rotation velocity of pump (r.p.m.)	1,375	1,360	1,340	1,290	1,240
Fluid volume of pumped storage (m.³/min.)	0.157	0.157	0.156	0.153	0.149
Vomiting head (m.)	6.5	8.0	10.0	15.0	19.0
Sucking head (m.)	8.45	8.2	8.2	7.75	8.84
Total head (m.)	14.9	16.2	18.2	22.7	27.8
Hydraulic power (k.w.)	3.84	4.15	4.16	5.80	7.35
Voltage (v.)	200	200	197	197	193
Electric current (a.)	8.4	9.0	8.8	13.0	13.0
Power factor	0.875	9.0	8.8	13.0	13.0
Efficiency, percent	0.757	9.0	8.8	13.0	13.0
Shaft power of pump (k.w.)	1.88	2.00	1.97	2.64	2.54
Pump efficiency, percent	49	48	42	46	40

TABLE 2.—READING DATA IN TESTING

Experiment No.	1	2	3	4
Voltage (v.)	200	200	197	193
Ampere (a.)	8.4	9.0	13	13
Rotation velocity (r.p.m.)	1,375	1,360	1,290	1,240
Vomiting volume (l./min.)	166	167	167	166
Vomiting pressure (drg.)	0.65	0.7	1.5	1.9
Sucking pressure (Hg.)	62	60	57	65

The pump, with its two joining piles of plural couples of rotors each mounting the two blades and the two recesses to shift each phase angle, transfers continuously and uniformly a greater amount of fluid with higher vomiting and sucking head, and without no priming fluid, under least vibration and noises.

The pump of the present invention may not decrease its functional efficiency if allowance between the blades or the rotors and the chamber is larger, as well as it may avoid perfectly cavitation phenomena which is caused when increasing rotation velocity because of each fluid storing room before and behind the chamber.

The suctorial inlet and the vomitory outlet may be mounted plurally according to usage of the pump.

The pump of the present invention may be produced smaller in its shape with greater efficiency and strength.

What I claim is:

1. A fluid pump having an 8-shape chamber comprising unit-casings to be combined and containing a main shaft and a subject shaft horizontally bridged over in the said chamber, the said both shafts having upper and lower trains of couples of rotors jointly contained each in the corresponding said unit-casing, the said rotors each having two mutually opposed projecting blades and two opposed recesses, each blade of one rotor fitting into the said recess of the other rotor, the said rotors being combined to shift their phase angles with respect to each other, the peripheral joint area of the said rotors contracting with partition walls mounted inside the said chamber slidingly, said partition walls being situated within said chamber at those locations where the phase angles shift, the said chamber having fluid storing rooms before and behind itself, and the said fluid storing rooms each projecting and having a volume larger than a suctorial inlet and pressure outlet.
